UNITED STATES PATENT OFFICE.

STANLEY MACOMBER, OF MASSILLON, OHIO, ASSIGNOR TO THE MACOMBER STEEL COMPANY, OF CANTON, OHIO, A CORPORATION OF OHIO.

BAR-BENDING MACHINE.

Application filed September 21, 1925. Serial No. 57,611.

The present improvements relate more particularly to a machine for bending straight bars either of round or other cross-section into zigzag shape, i. e. to form therein a succession of oppositely directed V's. Bars thus bent may be variously used in steel structural work as for example to form the web members of structural units such as the one known in the trade as Massillon bar joist, such joist being constructed by welding or otherwise rigidly securing such a web member at the bends therein to parallel chord members.

The object of the invention is to provide a machine whereon rods, even relatively heavy rods, may be expeditiously bent into the desired zigzag form without tearing or unduly cutting at the bends which must be avoided if a rod is to be used as a structural element in a unit having a predetermined load rating. A further object is to form the bends accurately and of uniformly the same angular degree so that the resulting product may be assembled without further manipulation in the manufacture of composite structural units such as the bar joist referred to above.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is partly a side elevation and partly a longitudinal vertical section of a bar bending machine embodying my present improvements; Fig. 2 is a plan view of the same; Fig. 3 is an end elevation thereof, as viewed from the left in Figs. 1 and 2; Figs. 4 and 5 represent diagrammatically successive operations in the bending of such a web bar; and Fig. 6 illustrates a section of the completed web bar.

The principal operative elements of the machine consist of two aligned stationary blocks 1 and 2 that have V-shaped notches formed in their opposed faces and will hereinafter be called female swages, and a block 3 that is reciprocable between said blocks 1 and 2 and will hereinafter be called a male swage. Said swages 1 and 2 are secured to supporting blocks 4 and 5, respectively, that are firm-

ly bolted to a table top 6, shims 4^a and 5^a being interposed between the swages and their respective supporting blocks whereby the positions of the female swages 1 and 2 may be adjusted. The male swage 3 is fitted between and secured to dogs 7 on a slide 8, such dogs projecting through a longitudinal slot 9 in the table top and such slide 8 being mounted in guides 10 that lie wholly beneath such table top. The upper surface of the latter, in other words, is clear of all projections save for the female swages 1 and 2, their supporting blocks and the male swage 3.

The driving mechanism for reciprocating the slide includes an eccentric 11 on a suitable power driven shaft 12 and a connecting rod or pitman 13 connected at one end with such eccentric and at the other end with a pin 14 on the under side of the slide 8. The driving eccentric, it will thus be seen, is centered below the center line of such slide which is a decided advantage in that the motion of the slide departs from a simple harmonic motion and becomes a slow steady one at the effective rod bending stage, with a more rapid reversing motion until the next bending operation is about to begin.

The first female swage 1 is formed with a V-shaped notch 1^a, while the other female swage is formed in its upper portion with a V-shaped notch 2^a and in its lower portion with a V-shaped notch 2^b of different angularity. As shown in Fig. 1, said swage 2 is, as a matter of convenience in construction, separated in a horizontal plane into two parts, the upper of which is formed with the notch or recess 2^a and the lower with the notch or recess 2^b. The ends of the male swage that project toward the respective female swages are correspondingly pointed although not on the same angle as are the recesses 1^a, 2^a and 2^b. The machine as shown is designed to make bends of four different angles, namely, 60 degrees, 120 degrees, 45 degrees and 90 degrees. The first two belong to the same bar always, while the latter two belong to one bar only. The male swages for these groups of bends will have an angularity of 55 degrees and 85 degrees, respectively, it being noted that the angles used in the female swages are less than the angle to be retained by the bar in order to produce strain enough to "set" the bar at the required angles which for the first group of bends are 118 degrees and 58 degrees, respectively, and for the sec-

ond group are 132 degrees and 88 degrees, respectively.

To eliminate tearing and cutting the bars while they are being bent, the points of the male swage are rounded, as shown, at a radius of not less than $\frac{1}{4}$ th inch, and the sides of the female swages should for the same reason be rounded at a radius of not less than $\frac{1}{2}$ inch.

10 Those portions 15 of the upper surface of slide 8 that project beyond the male swage 3 and lie between the sides of opening 9 slope downwardly and away from the swage for the purpose of carrying away any scale that may 15 be loosened from the bar during the bending operation. The table top 6, as shown, is made of a thick plate suitably reinforced, and the supporting frame 16 therefor should be of heavy construction and well braced to 20 prevent wracking. The swages will, of course, be desirably made of hardened steel.

As shown in Fig. 6, the finished bar A has its intermediate portion reversely bent at 25 points *a* at angles of 60 degrees, while the end portion *a'* of the bar, which extends in a direction parallel with the median line of the zigzag main body of such bar, forms an angle of 120 degrees with the adjacent web portion. Fig. 4 represents the operation of the 30 swages in forming a bend at such point *a*, while Fig. 5 similarly represents the operation in forming the bend between such portion *a'* and adjacent web portion. For the 35 purpose of making this last mentioned more obtuse bend, the lower notch 2^b in female swage 2 will be employed, while for forming the reversely directed angles at points *a*, notch 2^a in such swage and notch 1^a in the opposed swage will be used. A stop 17 on the 40 table top serves to gauge the rod A as it is moved forwardly to permit the successive bends thus to be formed therein.

Other modes of applying the principle of my invention may be employed instead of 45 the one explained, change being made as regards the mechanism herein disclosed, provided the means stated by any of the following claims or the equivalent of such stated means be employed.

50 I therefore particularly point out and distinctly claim as my invention:—

1. In mechanism for reversely bending bar-stock, the combination of a support on the order of a table top, two female swages secured to said top, the latter having a slot extending between said swages, a slide mounted on the under side of said top so as to be reciprocable longitudinally of such slot and wholly beneath said top and a unitary male swage mounted on said slide, the opposite ends of said male swage being formed to cooperate with said female swages, respectively. 55

2. In mechanism for reversely bending bar-stock, the combination of a support on the order of a table top, two female swages secured to said top, the latter having a slot extending between said swages, a slide mounted on said top so as to be reciprocable longitudinally of such slot, means for thus reciprocating said slide including an eccentric located beneath said top and a pitman connecting said eccentric with the under side of 60 said slide, and a male swage mounted on said slide, the opposite ends of said male swage being formed to cooperate with said female swages, respectively. 70

3. In mechanism for reversely bending bar-stock, the combination of a support on the order of a table top having a longitudinal slot 65 therein, supporting blocks on said top adjacent the respective ends of such slot, a female swage adjustably secured to the inwardly directed face of each of said blocks, guides on the underside of said top parallel with such slot, a slide reciprocably held in said 75 guides, dogs on said slide projecting upwardly through such slot, and a male swage removably held between said dogs, the opposite ends of said male swage being formed to cooperate with said female swages, respectively. 80

4. In mechanism for reversely bending bar-stock, the combination of a stationary female swage having two V-shaped notches 95 of different angularity one above the other in its operative face, and a male swage reciprocable towards and from said female swage and being pointed to enter the notches in said female swage. 90

Signed by me this 18 day of Sept., 1925.
STANLEY MACOMBER. 100
